UNITED STATES PATENT OFFICE.

SANDERS WALKER, OF WICHITA FALLS, TEXAS.

CARBURETER.

1,389,719.

Specification of Letters Patent. Patented Sept. 6, 1921.

Application filed July 5, 1919. Serial No. 308,845.

To all whom it may concern:

Be it known that I, SANDERS WALKER, a citizen of the United States, residing at Wichita Falls, in the county of Wichita 5 and State of Texas, have invented certain new and useful Improvements in Carbureters, of which the following is a specification.

My invention relates to improvements in 10 carbureters and in such connection it relates to that class of apparatus for carbureting air with the heavier liquid hydrocarbons, particularly crude oil.

The class of carbureters to which my 15 invention relates is described and illustrated in Letters Patent No. 703,995, dated July 8, 1902, granted to Fred E. Caton and Franklin B. Warring, and consists in certain improvements which are in line with 20 a carbureter of this description.

The principal object of my invention is to provide a carbureter of this type which shall be very simple in construction and 25 operation.

In carrying out my invention, I provide 30 a cylindrical casing inside of which a smaller cylinder is placed to act as a vaporizer, the exhaust from the engine being utilized to heat the small cylinder or vaporizer, onto which the crude oil is allowed 35 to flow and is thus vaporized by the heat. Suitable means are also employed to regulate the admission of air to the casing and to provide for the outlet of carbureted air.

My invention will be more fully understood from the following description, taken 40 in connection with the accompanying drawings forming part hereof in which—

Figure 1 is a side elevational view of a 45 carbureter embodying the main features of my invention.

Fig. 2 is a vertical sectional view.

Fig. 3 is a cross sectional view taken on line 3—3 of Fig. 2, and

Fig. 4 is a top view of one of the dampers.

Referring to the drawings, 1 represents the casing of the carbureter which has a top plate 2 bolted thereon and a bottom plate 3 with an opening to admit exhaust 50 from the engine through a pipe 4 attached to the casing in any suitable manner. The

exhaust gases from the engine entering through pipe 4 are carried into the vaporizer which consists of a cylinder 5 attached to which is a neck 6. The exhaust gases 55 from the engine passing up through pipe 4 heat the cylinder 5 and neck 6 constituting the vaporizer. The liquid to be vaporized, crude liquid hydrocarbon oil, for instance, enters through a feed pipe 7 from a 60 storage tank not shown and flows onto and around a collar 8 on the neck 6 of the vaporizer. This collar is constructed preferably of asbestos, although any suitable material 65 may be used. The oil is thus carried around the collar and flows down the neck 6 and onto the cylinder 5 of the vaporizer, the heat causing the oil to vaporize. Sufficient 70 gasoline is used to start the engine and as soon as the exhaust gases heat the vaporizer 75 sufficiently to vaporize the oil, such vapor is then used to carburet the air. The carbureted air passes out to the engine or engines through the pipes 9—9, as one or more engines can be operated by the same carbureter.

A series of inlet pipes 10—10 are placed around the carbureter casing 1 for the entrance of air, each pipe having a damper 11 for the control of the air admitted to 80 the casing 1. Such oil as is not vaporized falls to the bottom of the casing 1 and can be carried off through the pipe 12.

Having thus described the nature and objects of my invention, what I claim as 85 new and desire to secure by Letter Patent, is—

A carbureter having an exterior casing, a substantially large tubular heater or vaporizer completely inclosed within said casing, an inlet pipe connected to said exterior casing and to the vaporizer to admit exhaust gases from an engine to the vaporizer, 90 said vaporizer having its periphery smooth and extending from the bottom of the exterior casing to within a relatively short distance of the top thereof and connected to a tubular neck, said neck extending from the top of the vaporizer to and beyond the exterior casing and comprising an outlet 95 for said exhaust gases, in combination with a collar on said neck, a feed pipe project- 100

ing within the exterior casing and disposed over said collar to admit liquid to be vaporized by its distribution over said collar, neck and vaporizer by the heat of said exhaust gases, means on the upper end of the exterior casing for carrying off the vapor formed, and annularly disposed pipes on the

outside of the exterior casing in parallel relationship thereto for admission of air into the casing, and means for controlling the air.

In testimony whereof I have signed my name to this specification.

SANDERS WALKER.
